FOUNTAIN HAIRDRESSING COMB

Emmett Jefferson, New York, N. Y.

Application January 16, 1951, Serial No. 206,255

4 Claims. (Cl. 132—13)

1

This invention relates to implements used in hairdressing and particularly implements of the fountain type wherein materials are supplied through a handle to hollow comb teeth or other applying devices in the head, and in particular the invention relates to a comb having hollow V-shaped teeth carried by a head on the outer end of a tubular handle wherein means is provided for supplying oil or other hairdressing fluid to the hair from a reservoir in the handle through wicks in the sides of the head of the comb and in which valve means is provided for controlling the flow of fluid to the wicks.

The purpose of this invention is to provide an improved hairdressing comb of the fountain type wherein a hollow comb with wicks in the sides of the head thereof is rotated by a thumb lever on the handle whereby the head is rotated in the hair to efficiently apply fluid to the hair. This invention is an improvement over the hairdressing comb of my prior Patent No. 2,267,031 of December 24, 1941, in that wicks are provided in the sides of the head and plungers are provided in the handle for resiliently urging the fluid feeding means toward the head.

Various attempts have been made to apply grease, oil, dye and the like to the hair but it has been found difficult to thoroughly saturate the hair without using an excess of the material. With this thought in mind this invention contemplates a hair dressing device including a hollow comb with a head rotatably mounted on a cylinder extended from a handle and in which the cylinder with the comb thereon may be rotated by a button or thumb lever pivotally mounted on the handle.

The object of this invention is, therefore, to provide means for mounting a comb on the end of a handle in a hairdressing implement of the fountain type wherein with saturated wicks in the sides of the head of the comb fluids are readily applied to the hair by rotating the comb on the end of the handle.

Another object of the invention is to provide a rotatable comb head having wicks in the sides thereof carried by the end of a handle in which means is provided for regulating the flow of fluids from the handle to the wicks.

A further object of the invention is to provide a hairdressing implement including a hollow toothed comb with wicks in the sides thereof and with means for rotating the comb head, which is of a simple and economical construction.

With these and other objects and advantages in view the invention embodies a tubular handle having a plunger therein with a hollow toothed comb carried by cylindrical heads journaled in the end of the handle and provided with wicks in the sides of the head and means for applying

2

fluid from the handle to the wicks as the head is rotated.

Other features and advantages of the invention will appear from the following description taken in connection with the drawings wherein:

Figure 1 is a side elevational view showing the improved hairdressing comb.

Figure 2 is a sectional plan through the comb taken on line 2—2 of Figure 1.

Figure 3 is a view looking upwardly toward the under side of the implement taken on line 3—3 of Figure 1.

Figure 4 is a cross section through the comb and head being taken on line 4—4 of Figure 1.

Figure 5 is a similar section taken on line 5—5 of Figure 1, and showing the head in the free position.

Figure 6 is a similar section showing the comb and head rotated through an angle of substantially 90° and with the operating lever positioned against the outer surface of the handle.

Figure 7 is a detail illustrating the device for opening the valve in the head of the comb as the head and comb are rotated.

Figure 8 is a plan view of the valve actuating means shown in Figure 7.

Figure 9 is a view showing the outer end of the tubular handle of the implement illustrating the method of filling a reservoir in the handle from a jar or other container.

Referring now to the drawings wherein like reference characters denote corresponding parts the improved fountain hairdressing comb of this invention includes a comb having substantially hollow teeth with a tooth 16 at the outer end of a tubular handle 12, a cylindrical casing 13 providing a reservoir in the handle, a thumb lever 14 for rotating the comb and head, and a thermometer 15.

The comb is provided with a plurality of spaced hollow teeth with a tooth 16 at the outer end and a comparatively wide tooth 17 at the inner end. The comb is secured, preferably by welding, to the lower surface of the cylinder 11 and a strap 18 may be provided around the outer end of the cylinder.

The cylinder 11 is provided with recesses 19 and 20 in the opposite sides and wicks 21 and 22, respectively, positioned in the recesses are supplied with oil or other fluid through spaced passages 23 and 24 that communicate with an inner opening 25 in the center of the cylinder, as illustrated in Figures 2 and 4. The opening 25 is supplied with fluid from the reservoir in the casing

13 by a passage 26 extended through the inner end of the cylindrical head 11 and a tubular stem 27 that extends from the casing 13 to the passage 26. One end of the stem 27 is threaded into the head 11 at the point 28 and the other end is threaded into the head 29 of the casing 13.

as shown at the point 30. A tension spring 31 is positioned around the stem with one end 32 secured in the end 33 of the handle and with the opposite end 34 secured in the head 29; the spring will wind as the head 11 of the comb is rotated by the thumb lever 14 whereby upon release of the thumb lever the spring will return the comb to the position shown in Figures 1 and 4.

A control rod 35 with a valve shaped inner end 36 that coacts with the valve seat 37 in the end of the passage 26 of the head is threaded in a bushing 38 in the outer end of the head and the outer end of the rod is provided with a head 39 by which the position thereof may be adjusted to regulate the flow of fluid from the reservoir to the wicks. The wicks 21 and 22 are secured in the recesses 19 and 20 by screws 40, as shown in Figure 2.

The inner end of the head 11 is journaled in the end section 33 of the handle by a ball bearing 41 and as the thumb lever 14 is pressed inwardly the arcuate end 42 thereof which is connected to a projection 43 on the head 11 by a link 44 draws the projection around to the position shown in Figure 6 wherein lever 45 on a conical shaped valve 46, that is mounted in a similarly shaped opening 47 in the head 11, rotates the valve so that an opening 48 through the valve registers with the passage 26 in the inner end of the cylindrical head 11.

The lever 45 is normally held against the projection 49 extended from the end 33 of the handle 12 by a spring 50 on a stem 51 of the valve 46 and as the cylinder is rotated by the thumb lever 14 from the position shown in Figure 5 to that shown in Figure 6 the lever 45 moves from the position shown in full lines in Figure 7 to that shown in dotted lines whereby the valve 46 rotates so that the opening 48 registers with the opening 26. A stop 51a is provided to limit the opening movement of the valve and as the cylinder 11 is returned by the spring 31 the lever 45 is actuated by a member 49 whereby the valve is returned to the position shown in Figures 5 and 7. The thumb lever 14 is journaled in a projection 52 that extends from one side of the end 33 of the handle.

The handle 12 which is formed as illustrated in Figure 2 is secured to the end 33 by screws 53 and the bearing bushing 54 is provided in the outer end to facilitate rotation of the casing 13.

A head 55 with a tubular stem 56 extended from the inner side thereof is threaded in the outer end of the tubular casing 13 and a tubular stem 57 of a plunger 58 telescopes over the stem 56 whereby pressure is exerted upon the fluid in the reservoir 59 of the casing 13 by a spring 60.

As illustrated in Figure 9 the head 55 of the plunger 58 may be removed and a filling head 61 with a jar or container 62 connected to a stem 63 thereof by a tube 64 may be threaded in the end of the casing 13 to replenish the supply of fluid therein.

The end of the comb may be provided with an extension 65 by which the inner end thereof may be secured to the head 11 by a screw 66 which with the band 18 provides means for securing the comb to the cylindrical head without welding, if desired.

With the parts arranged in this manner oil, grease, dye or other lubricant may be supplied from a container 62 to the reservoir 59 and when

the reservoir is filled the head 61 is removed and replaced by the plunger 58 and head 55. The valve 46 closes the passage 26 between the reservoir and the opening 25 that feeds the wicks 21 and 22 and when the cylindrical head is rotated by the thumb lever 14 the valve is opened to admit a charge of fluid through the chamber 25 and from the chamber 25 the fluid passes to the wicks through the spaced openings 23 and 24.

10 For some uses in dressing the hair it is desired to heat the fluid and also the comb and where heat is used the thermometer 15 indicates the temperature whereby scorching the hair is prevented.

15 The control of the fluid through the passage 26, after the valve 46 is opened is controlled by the valve element 36 on the control rod 35.

It will be understood that modifications may be made in the design and arrangement of the 20 parts without departing from the spirit of the invention.

What is claimed is:

1. A hair dressing fountain comb comprising a tubular handle, a cylindrical head rotatably 25 mounted in the end of the handle, a comb having teeth extended from one side of the head, a cylindrical casing having a reservoir therein journaled in the said handle, a spring actuated plunger positioned in said casing, wicks positioned on the sides of the head, there being a passage extended from the reservoir of the handle through the cylindrical head to the wicks.

2. A hair dressing fountain comb comprising a tubular handle, a cylindrical head rotatably 35 mounted in the end of the handle, a comb having teeth extended from one side of the head, a cylindrical casing having a reservoir therein journaled in the said handle, a spring actuated 40 plunger positioned in said casing, wicks positioned on the sides of the head, there being a passage extended from the reservoir of the handle through the cylindrical head to the wicks, and means rotating the said cylindrical head in the handle.

45 3. A hair dressing fountain comb comprising a tubular handle, a cylindrical head rotatably mounted in the end of the handle, a comb having teeth extended from one side of the head, a cylindrical casing having a reservoir therein journaled in the said handle, a spring actuated 50 plunger positioned in said casing, wicks positioned on the sides of the head, there being a passage extended from the reservoir of the handle through the cylindrical head to the wicks, a valve in the said passage, and means rotating the cylindrical head.

4. A hair dressing fountain comb comprising a tubular handle, a cylindrical head rotatably mounted in the end of the handle, a comb having teeth extended from one side of the head, a cylindrical casing having a reservoir therein journaled in the said handle, a spring actuated 60 plunger positioned in said casing, wicks positioned on the sides of the head, there being a passage extended from the reservoir of the handle through the cylindrical head to the wicks, a valve in the said passage, means rotating the cylindrical head, and means opening the valve as the said cylindrical head is rotated.

EMMETT JEFFERSON.
